UNITED STATES PATENT OFFICE

LOUIS PIROLA, OF CHICAGO, ILLINOIS, ASSIGNOR TO THE HARRINGTON & KING PERFORATING COMPANY, OF CHICAGO, ILLINOIS, A CORPORATION OF ILLINOIS

DESIGN FOR A GRILLE PANEL

Application filed May 23, 1932. Serial No. 43,885. Term of patent 14 years.

To all whom it may concern:

Be it known that I, LOUIS PIROLA, a citizen of the United States, having residence in the city of Chicago, county of Cook, and State of Illinois, have invented a new, original, and ornamental Design for a Grille Panel, of which the following is a specification, reference being had to the accompanying drawing, forming a part thereof.

In the drawing:

The figure is a plan view of part of a grille

panel embodying my new design. It may be understood that this design is applied to flat (or sheet) material of relatively slight depth or thickness for producing a grille adapted to be used as a panel for a door, screen, radiator or similar article.

I claim:

The ornamental design for a grille panel substantially as shown and described.

LOUIS PIROLA.
